Primary Examiner — Ricky Pham(74) *Attorney, Agent, or Firm* — Kalow & Springut, LLP(57) **CLAIM**

The ornamental design for a deep grilling topper, as shown and described.

DESCRIPTION

FIG. 1 is a front perspective view of the deep grilling topper. FIG. 2 is a left side view of the deep grilling topper. FIG. 3 is a top side view of the deep grilling topper. FIG. 4 is a right side view of the deep grilling topper. FIG. 5 is a back view of the deep grilling topper. FIG. 6 is a bottom view of the deep grilling topper; and, FIG. 7 is a front view of the deep grilling topper. The broken lines shown in the drawings are for illustrative purposes only and form no part of the claimed design.
